CLAIM

The ornamental design for an animal transportation container, as shown and described.

DESCRIPTION

FIG. 1 is a perspective view of an animal transportation container showing our new design;
 FIG. 2 is a side elevational view thereof, the opposite side elevational view being a mirror image;
 FIG. 3 is a rear elevational view thereof;
 FIG. 4 is a front elevational view thereof;
 FIG. 5 is a top plan view thereof;
 FIG. 6 is a bottom plan view thereof; and,
 FIG. 7 is a perspective view of the embodiment shown in FIG. 1 with one door and the top in an open position.

FIG. 1

FIG. 2

FIG. 3

FIG. 4

FIG. 5

FIG. 6

FIG. 7
